UNITED STATES PATENT OFFICE.

BERNARD M. FINE, OF PHILADELPHIA, PENNSYLVANIA.

PRESS.

Application filed March 2, 1923. Serial No. 622,269.

To all whom it may concern:

Be it known that I, BERNARD M. FINE, a citizen of the United States, residing at Philadelphia, Pennsylvania, have invented 5 certain new and useful Improvements in Presses, of which I declare the following to be a full, clear, and exact description.

My invention relates to improvements in presses and has to do, more particularly, 10 with presses of the general type employed for repressing bricks, or similar material, which have been roughly formed in a previous operation.

Practically all presses in use, at the 15 present time, for repressing bricks are hand-operated and are very slow and inefficient in operation. The operator moves a closure to one side, opening the mold chamber, grasps a brick to be pressed, inserts it in the 20 mold chamber, moves the closure to position to close the mold chamber, operates the hand lever which applies pressure to the brick in the mold chamber, moves the closure to one side to open the mold chamber, and 25 then removes the pressed brick. These many hand operations slow down the operation of the machine and decrease its output very materially.

The chief object of my invention is to provide 30 a press, suitable for repressing brick, which is largely automatic in operation so that the output from such a machine is largely increased over that possible with prior machines and the cost of operation is 35 reduced.

A further object of my invention is to provide 40 a power-actuated press which is set in motion automatically when the closure for the mold chamber is moved to closed position.

A further object of my invention is to provide 45 a press of this character in which the power is automatically disconnected after a predetermined movement of the pressure mechanism.

Another object of my invention is to provide 50 a press of the kind described in which the power is automatically disconnected from the pressure mechanism when the closure for the mold chamber is in open position.

A further object of my invention is to provide 55 a press of the general character described including a mold chamber and a movable closure for such mold chamber

which is moved toward the mold chamber by suitable connections with a source of power, said connections being yielding so as to take care of variations in the size of the 60 bricks received in said mold chamber.

A further object of my invention is to provide 65 a portable, self-contained, motor-driven brick press of the kind described, which may be moved very easily from place to place with reference, for instance, to a pile of bricks which are to be run through the press.

Another object of my invention is to provide 70 a press which has a slow motion during a part of the stroke and a faster motion during another part of the stroke.

Further objects, and objects relating to 75 details and economies of operation and construction, will definitely appear from the detailed description to follow. In one instance, I accomplish the objects of my invention by the devices and means set forth in the accompanying specification. My invention is clearly defined and pointed out in the appended claims. A structure constituting 80 a preferred embodiment of my invention is illustrated in the accompanying drawings, forming a part of this specification, in which:

Fig. 1 is a view, in side elevation, of a 85 machine embodying my invention, part of the frame being broken away to show the gearing.

Fig. 2 is a horizontal, sectional view, taken 90 on the line 2—2 of Fig. 1.

Fig. 3 is a vertical, sectional view, taken 95 on the line 3—3 of Fig. 1, the driving motor and fly wheel being shown in full lines.

Fig. 4 is a longitudinal, sectional view on the line 4—4 of Fig. 2.

Fig. 5 is a longitudinal, sectional view on the line 5—5 of Fig. 2.

Fig. 6 is a view, corresponding to the left-hand part of Fig. 1, showing a modified 100 form of my invention, and

Fig. 7 is a vertical, sectional view on the line 7—7 of Fig. 6.

In the drawings, the same reference numerals refer to the same parts throughout the several views, and the sectional views 105 are taken looking in the direction of the arrows at the ends of the section lines.

Referring to the numbered parts of the drawings, I have illustrated a machine embodying my invention and including a 110

framework, 10, mounted upon supporting wheels or rollers, 11, so that it may be moved from place to place without difficulty. This framework carries a part, 12, 5 forming the side walls of the mold chamber. The bottom wall of the mold chamber is formed by the head, 14, of the plunger, 13, which is mounted so as to be reciprocated within the mold chamber. The top wall of 10 the mold chamber is formed by a closure plate, 15, which is carried by a closure yoke, having the legs, 17, and the cross member, 16. The closure plate, 15, and the plunger, 13, are moved toward each other in the 15 operation of the machine in order to exert pressure upon the brick, or other material to be pressed, which is confined in the mold chamber. To secure such movement of the parts, the legs, 17, of the closure yoke are 20 pivotally connected to the actuating lever, 23, and the lever, or a part carried by it, engages the lower end of the plunger to exert an upward pressure thereon. In the 25 machine shown, the half-round bearing seats, 18, are formed at the lower ends of the legs, 17, fitting the laterally-extending trunnions, 20, on the actuating lever, 23. The bearing members, 19, have half-round seats complementary to the seats, 18, and 30 these bearing members are yieldingly connected to the lower ends of the legs, 17, by the bolts, 21, which extend from the lower ends of the legs, 17, through the bearing members, 19, and the springs, 22, disposed 35 on said bolts between the members, 19, and the nuts, 19', screwed on the ends of the bolts. The bearing seats, 18, and the members, 19, together form bearings which receive the trunnions, 20, on the actuating 40 lever and form a pivotal connection between the closure yoke and said lever. This connection is yielding, however, so that, in case an oversize brick is placed in the mold chamber, the connection between the lever and 45 the closure yoke will yield and prevent the breaking of the machine. Notches, 26, are provided in the upper edge of the actuating lever which receive the trunnions, 27, of a roller, 28, which bears against the foot, 29, 50 on the lower end of the plunger, 13. A cross bar, 25, extends between the sides of the frame, 10, and serves as a fulcrum for the lever, 23, when the closure plate, 15, is not in engagement with the top of the mold chamber. A nose, 24, at the end of the lever is adapted to engage said cross bar.

The lever, 23, is power-actuated, being 55 operated by the driven shaft, 40, which is suitably journaled in the frame of the machine. This shaft is driven from the electric motor, 33, through a train of reducing gearing including the pinion, 35, on the armature shaft, 34, the gear, 36, on the stub shaft, 37, which meshes with said pinion, 60 and the pinion, 38, on said stub shaft, mesh-

ing with the gear, 39, fast on said shaft, 40. A bell-crank lever, 44, is loosely mounted on said shaft, 40, and one arm of said bell-crank is connected to the end of the actuating lever, 23, by a link, 30, which is pivotally connected to the actuating lever, at 31, and to the bell-crank arm, at 32. The bell-crank, 44, is connected to the shaft, 40, so as to rotate therewith, by suitable clutch mechanism. In the machine illustrated, this 70 clutch mechanism comprises a disk, 41, which is fast on the shaft, 40, and provided with a plurality of peripheral notches, 42, and a pawl, 45, which is pivoted, at 48, to the arm 43, of the bell-crank, 44. This pawl 75 has a head, 46, adapted to engage in any one of the notches in the disk, 41, and the pawl is normally held in such position that said head, 46, engages in one of said notches, by a spring, 75. The pawl is also provided 80 with a tail, 47, by which it may be withdrawn from engagement in the manner to be described hereinafter.

It will be observed that, due to the pivotal connection between the closure yoke and the actuating lever, the former may be swung to one side to the position shown in Fig. 4, to permit the removal of the brick from the mold chamber. It is desired to provide means whereby the clutch mechanism between the shaft, 40, and the actuating lever, 23, is disconnected when the closure yoke is swung to the open position and whereby said clutch is automatically connected when the closure yoke is swung to closed position. I have accomplished this by providing a trip, 49, which is slidably mounted in a portion, 50, of the frame, 10, so that, when the trip is projected, its nose is in position to engage the tail, 47, of the pawl when the latter is carried past by the rotation of the shaft, 40. This trip, 49, is normally held in projected position by a spring, 51, on the stem, 52, extending rearwardly from said trip, said spring being compressed between the portion, 50, of the frame and the nut, 53, at the end of said stem. The trip, 49, carries a pin, 54, which extends through a slot, 55, to the outside of the frame. A trip-withdrawing link, 56, is pivotally connected, 115 at 57, with an arm, 58, depending from one of the bearing members, 19. This link extends forwardly and has an arm, 59, carrying an adjustable stop screw, 60, which is adapted to engage the pin, 54, to hold the trip in retracted position, when the closure yoke is in closed position as shown in Fig. 1. When the closure yoke is in open position, the link is thrown forwardly, due to its connection with the arm, 58, so that the trip moves under the pressure of spring, 51, to projected position.

It is desirable to disconnect the clutch mechanism automatically after the bell-crank has completed one revolution with 120

the shaft, 40. In order to accomplish this, I have provided an arm, 61, on the link, 56, which extends forwardly through a slot, 79, in the casing, 76, enclosing the reducing 5 gearing. An arm, 63, is fixed on the shaft, 40, and has an offset end, 64, which strikes the offset end, 62, of the arm, 61, when the closure yoke is in closed position. This lifts the link so that the stop screw, 60, 10 clears the pin, 54, and the trip, 49, is moved by the spring, 51, to projected position in which it engages the tail, 47, of the pawl and retracts the pawl. When the closure yoke is in open position, the offset ends, 62 and 64, 15 occupy such positions with respect to each other that they do not strike. At such times, the trip is always in projected position and it is not necessary for the arm, 63, to strike the arm, 61, and lift the link.

20 The removal of the brick is facilitated by the knock-out, 65, having a stem, 66, sliding in the plunger, 13. This stem is engaged by the lever, 70, pivoted at 71, and extending through a slot, 68, in the bearing, 69, for 25 the plunger, 13, and a slot, 67, in the plunger. The lever, 70, is actuated by a link, 73, connected to a foot lever, 74, and held normally withdrawn by the spring, 72.

From the foregoing description, the operation 30 of the machine should be very readily understood. When the closure yoke is in the position shown in Fig. 4, the brick or material to be pressed is inserted in the mold chamber, 12. The closure yoke is then swung to closed position so that the closure plate, 15, closes the top of the mold chamber. The brick rests upon the head, 14, of the plunger, 13. The movement of the closure yoke to closed position moves the link, 56, rearwardly, causing the stop screw, 60, to engage the pin, 54, and withdraw the trip, 49, from projected position. This releases the pawl, 45, and the spring, 75, causes it to engage in one of the notches of the disk, 41. This connects the bell-crank, 44, to the shaft, 40, so that it is caused to rotate therewith and the actuating lever, 23, is oscillated. As the shaft, 40, rotates, the offset end, 64, of the arm, 63, engages the offset end, 62, of the arm, 61, and lifts the link, 56, releasing the trip. The trip moves to projected position and engages and retracts the pawl, 45, when the latter comes past, thus disconnecting the clutch mechanism and bringing the actuating lever to rest. The operator now swings the closure yoke to open position and removes the pressed brick, with the assistance of the knock-out, 65. It is to be noted that this machine is largely automatic and 50 all the operator has to do is to swing the closure yoke to and from closed position, remove the pressed brick and insert a new one to be pressed. The drive for the actuating lever is controlled by the position of the closure for the mold chamber, and it is auto-

matically connected when the closure is moved to closed position.

In some cases, it is desirable to have a slow motion for a part of the stroke of the plunger in order to apply the final pressure to the material slowly. In such cases, in order to avoid slowing down the machine too much, I find it desirable to provide a faster motion for another part of the plunger stroke. I have accomplished this, in the present machine, by the modified construction shown in Figs. 6 and 7, in which I introduce a pair of elliptic gears in the train of reducing gearing leading to the driven shaft, 40. The gear, 39, instead of being on the shaft, 40, is mounted on a stub shaft, 80, to which is keyed the elliptic gear, 81, meshing with the elliptic gear, 82, fast on the driven shaft, 40. As a result of this arrangement of gearing, the latter part of the pressure stroke and the first part of the return stroke are much slower than the first part of the pressure stroke and the last part of the return stroke. The connections between the driven shaft and the actuating lever may be the same as in the preferred form of my invention but I am not to be restricted to such arrangement.

I am aware that the machine described in this specification may be changed considerably without departing from the spirit of my invention and, therefore, I desire to claim my invention broadly, as indicated by the appended claims.

Having thus described my invention, what I claim as new and useful and desire to secure by Letters Patent is:

1. A press of the kind described comprising a mold chamber adapted to receive the material to be pressed, means for exerting a pressure upon the material in said mold chamber, driving mechanism for actuating said means, means for opening and closing the mold chamber, and means for automatically disconnecting said driving mechanism when the mold chamber is opened.

2. A press of the kind described comprising a mold chamber adapted to receive the material to be pressed, a driven shaft, pressure means acting on the material in said chamber, operating connections between said shaft and said pressure means including a clutch, means for opening and closing said mold chamber, and means for automatically actuating said clutch to disconnect the pressure means from the driven shaft when the mold chamber is opened.

3. A press of the kind described comprising a mold chamber adapted to receive the material to be pressed, means for opening and closing said chamber, pressure means acting on the material in said chamber and including an actuating lever, a driven shaft, and means for actuating said

lever from said driven shaft, said means being automatically rendered inoperative when the mold chamber is opened.

4. A press of the kind described comprising a mold chamber adapted to receive the material to be pressed, means for opening and closing said mold chamber, pressure means acting on the material in said chamber, and including an actuating lever, 10 a driven shaft, a crank arm mounted on said shaft and connected to said lever, and means connecting said crank arm to said shaft so as to rotate therewith, said means being automatically disconnected when the 15 chamber is opened.

5. A press of the kind described comprising a mold chamber adapted to receive the material to be pressed, means for opening and closing said chamber, pressure 20 means acting on the material in said chamber and including an actuating lever, a driven shaft, a disk fixed thereon and having a plurality of peripheral notches, an arm journaled on said shaft and having 25 one end connected to said lever, a pawl carried by the opposite end of said arm and normally engaging in one of the notches of said disk, and means for automatically withdrawing said pawl from engagement with the disk when the mold 30 chamber is opened.

6. A press of the kind described comprising a mold chamber adapted to receive the material to be pressed, means for opening 35 and closing said chamber, pressure means acting on the material in said chamber, a driven shaft, operating connections between said shaft and pressure means including a clutch, and means, operated automatically when the chamber is closed, for actuating said clutch to connect the shaft and pressure means.

7. A press of the kind described comprising a mold chamber adapted to receive the material to be pressed, means for opening 45 and closing said mold chamber, pressure means acting on the material in said chamber, and including an actuating lever, a driven shaft, and means for automatically connecting said lever to said shaft when the 50 chamber is closed.

8. A press of the kind described comprising a mold chamber adapted to receive the material to be pressed, means for opening 55 and closing said chamber, pressure means acting on the material in said chamber and including an actuating lever, a driven shaft, a crank arm journaled on said shaft and connected to said lever, and means automatically connecting said crank arm to the shaft to rotate therewith when the chamber is closed.

9. A press of the kind described comprising a mold chamber adapted to receive 65 the material to be pressed, means for open-

ing and closing said chamber, pressure means acting on the material in said chamber and including an actuating lever, a driven shaft, a disk fixed thereon and having a plurality of peripheral notches, an arm journaled on said shaft and having one end connected to said lever, a pawl carried by the opposite end of said arm, and means for automatically moving said pawl into engagement with one of the notches of said disk when the mold chamber is closed.

10. A press of the kind described comprising a mold chamber adapted to receive the material to be pressed, means for opening and closing said chamber, pressure means acting on the material in said chamber, a driven shaft, means for automatically connecting said shaft and pressure means when the chamber is closed, and means for automatically disconnecting said shaft and pressure means after a predetermined movement of the pressure means.

11. A press of the kind described comprising a mold chamber adapted to receive the material to be pressed, means for opening and closing said chamber, pressure means acting on the material in said chamber, a driven shaft, operating connections between said shaft and pressure means including a clutch, means, operated automatically when the chamber is closed, for actuating said clutch to connect the shaft and pressure means, and means, operated automatically after a predetermined movement of the pressure means, for actuating the clutch to disconnect the shaft and pressure means.

12. A press of the kind described comprising a mold chamber adapted to receive the material to be pressed, means for opening and closing said mold chamber, pressure means acting on the material in said chamber and including an actuating lever, a driven shaft, means for automatically connecting said lever to said shaft when the chamber is closed, and means for automatically disconnecting the lever from said shaft after a predetermined movement of the lever.

13. A press of the kind described comprising a mold chamber adapted to receive the material to be pressed, means for opening and closing said chamber, pressure means acting on the material in said chamber and including an actuating lever, a driven shaft, a crank arm journaled on said shaft and connected to said lever, means automatically connecting said crank arm to said shaft to rotate therewith when the chamber is closed, and means for automatically disconnecting said crank arm from the shaft after a predetermined movement of the lever.

14. A press of the kind described com-

prising a mold chamber adapted to receive the material to be pressed, means for opening and closing said chamber, pressure means acting on the material in said chamber, and including an actuating lever, a driven shaft, a disk fixed thereon and having a plurality of peripheral notches, an arm journaled on said shaft and having one end connected to said lever, a pawl carried by the opposite end of said arm, means for automatically moving the pawl into engagement with one of said notches when the chamber is closed, and means for automatically disengaging said pawl after a predetermined movement of the actuating lever.

15. A press of the kind described comprising a mold chamber adapted to receive the material to be pressed, pressure means acting on the material in said chamber, actuating mechanism for said pressure means, and a movable closure for said chamber, said actuating mechanism being controlled by the position of said closure.

20. A press of the kind described comprising a mold chamber adapted to receive the material to be pressed, pressure means acting on the material in said chamber, driving mechanism, actuating connections between said driving mechanism and said pressure means, and a movable closure for said chamber, said actuating connections being controlled by the position of said closure.

25. A press of the kind described comprising a mold chamber adapted to receive the material to be pressed, pressure means acting on the material in said chamber, a driven shaft, a movable closure for said chamber, and a clutch connecting said shaft and pressure means and controlled by the position of said closure.

30. A press of the kind described comprising a mold chamber adapted to receive the material to be pressed, pressure means acting on the material in said chamber and including an actuating lever, a driven shaft, a crank arm mounted on said shaft and connected to said lever, a clutch for connecting said shaft and crank arm, and a movable closure for said chamber, said clutch being controlled by the position of said closure.

35. A press of the kind described comprising a mold chamber, a movable closure forming one wall of said chamber, a plunger forming another wall of said chamber, an actuating lever connected to move said closure and plunger toward each other, a driven shaft, and means for actuating said lever from said shaft.

40. A press of the kind described comprising a mold chamber, a movable closure forming one wall of said chamber, a plunger forming another wall of said chamber, an actuating lever connected to move said closure and plunger toward each other, a

driven shaft, and a crank arm connected to said lever and adapted to be connected to rotate with said shaft.

45. A press of the kind described comprising a mold chamber, a movable closure forming one wall of said chamber, a plunger forming another wall of said chamber, an actuating lever connected to move said closure and plunger toward each other, a driven shaft, a crank arm connected to said lever, and a clutch adapted to connect the crank arm to rotate with the shaft.

50. A press of the kind described comprising a mold chamber, a plunger forming the bottom wall of said chamber, an actuating lever having a laterally-extending trunnion, said lever engaging and actuating said plunger, a closure-carrying member yieldingly journaled on said trunnion, a closure carried by said member and forming the top wall of said chamber, and means for actuating said lever.

55. A press of the kind described comprising a mold chamber, a plunger forming the bottom wall of said chamber, an actuating lever having a pair of laterally-extending trunnions, said lever engaging and actuating said plunger, a closure yoke straddling said chamber and having its legs yieldingly journaled on said trunnions, a closure carried by said yoke and forming the top wall of said chamber, and means for actuating said lever.

60. A press of the kind described comprising a mold chamber, a plunger forming the bottom wall of said chamber, an actuating lever having a pair of laterally-extending trunnions, said lever engaging and actuating said plunger, a closure yoke straddling said chamber, the lower end of each leg of said yoke having a bearing engaging one of said trunnions, complementary bearing blocks, springs yieldingly holding said blocks in engagement with the trunnions and the ends of said legs, a closure carried by said yoke and forming the top wall of said chamber, and means for actuating said lever.

65. A press of the kind described comprising a mold chamber, a plunger forming the bottom wall of said chamber, an actuating lever having a pair of laterally-extending trunnions, said lever engaging and actuating said plunger, a closure yoke straddling said chamber, the legs of said yoke having at their lower ends split bearings journaled on said trunnions, and yieldingly held together, a closure carried by said yoke and forming the top wall of said chamber, and means for actuating said lever.

70. A press of the kind described comprising a mold chamber, a plunger forming the bottom wall of said chamber, a lever engaging and actuating said plunger, a closure yoke straddling said chamber and hav-

ing its legs pivotally connected to said lever, a closure carried by said yoke and forming the top wall of said chamber, a motor, and actuating connections between said motor and lever.

27. A press of the kind described comprising a mold chamber, a plunger forming the bottom wall of said chamber, a lever, engaging and actuating said plunger, a closure yoke straddling said chamber and having its legs pivotally connected to said lever, a closure carried by said yoke and forming the top wall of said chamber, a driven shaft, a crank arm connected to said lever, and means for connecting said crank arm to rotate with said shaft.

28. A press of the kind described comprising a mold chamber, a plunger forming the bottom wall of said chamber, a lever engaging and actuating said plunger, a closure yoke straddling said chamber and having its legs pivotally connected to said lever, a closure carried by said yoke and forming the top wall of said chamber, a driven shaft, a crank arm journaled on said shaft and connected to said lever, a clutch connecting said crank arm to said shaft, and means for automatically engaging said clutch when the closure yoke is moved to chamber-closing position.

29. A press of the kind described comprising a mold chamber, a plunger forming the bottom wall of said chamber, a lever engaging and actuating said plunger, a closure yoke straddling said chamber and having its legs pivotally connected to said lever, a closure carried by said yoke and forming the top wall of said chamber, a driven shaft, a crank arm journaled on said shaft and connected to said lever, a clutch connecting said crank arm to said shaft, means for automatically engaging said clutch when the yoke is moved to chamber-closing position, and means for automatically disengaging said clutch after a predetermined movement of the lever.

30. A press of the kind described comprising a mold chamber, a plunger forming the bottom wall of said chamber, a lever engaging and actuating said plunger, a closure yoke straddling the chamber and having its legs pivotally connected to said lever, a closure carried by said yoke and forming the top wall of said chamber, a driven shaft, a disk fixed on said shaft and provided with a plurality of peripheral notches, an arm journaled on said shaft and having one end connected to said lever, a pawl pivoted on the opposite end of said arm and adapted to engage in any one of the notches on said disk, a trip normally spring-pressed into position to engage the tail of the pawl and withdraw the latter from engagement with said disk, and means, actuated by movement of said yoke to chamber-closing position, for withdrawing said trip from operative position.

31. A press of the kind described comprising a mold chamber, a plunger forming the bottom wall of said chamber, a lever engaging and actuating said plunger, a closure yoke straddling said chamber and having its legs pivotally connected to said lever, a closure carried by said yoke and forming the top wall of said chamber, a driven shaft, a disk fixed on said shaft and having a plurality of peripheral notches, an arm journaled on said shaft and having one end connected to said lever, a pawl pivoted on the other end of said arm and adapted to engage in any one of said notches, a sliding trip normally spring-pressed into position to engage the tail of the pawl and withdraw the latter from engagement with said disk, and a trip-withdrawing link connected to one of the legs of said yoke and having a portion engaging said trip, whereby, when the yoke is moved to chamber-closing position, the trip is automatically withdrawn from the path of the pawl.

32. A press of the kind described comprising a mold chamber, a plunger forming the bottom wall of said chamber, a lever engaging and actuating said plunger, a closure yoke straddling said chamber and having its legs pivotally connected to said lever, a closure carried by said yoke and forming the top wall of said chamber, a driven shaft, a disk fixed on said shaft and having a plurality of peripheral notches, an arm journaled on said shaft and having one end connected to said lever, a pawl pivoted on the other end of said arm and adapted to engage in any one of said notches, a sliding trip normally spring-pressed into position to engage the tail of the pawl as the latter moves past it to withdraw said pawl from engagement with the disk, a trip-withdrawing link connected to one of the legs of said yoke and having a portion engaging said trip, whereby, when the yoke is moved to chamber-closing position, the trip is automatically withdrawn from the path of the pawl, and an arm fixed on said shaft and adapted to engage a portion of said link to release said trip and permit it to move into the path of said pawl.

33. A press of the kind described comprising a mold chamber, a plunger forming the bottom wall of said chamber, a lever engaging and actuating said plunger, a closure yoke straddling said chamber and having its legs pivotally connected to said lever, a closure carried by said yoke and forming the top wall of said chamber, a driven shaft, a disk fixed on said shaft and having a plurality of peripheral notches, an arm journaled on said shaft and having one end connected to said lever, a pawl pivoted on the other end of said arm and adapted to engage in any one of the notches on said disk, a trip normally spring-pressed into position to engage the tail of the pawl and withdraw the latter from engagement with said disk, and means, actuated by movement of said yoke to chamber-closing position, for withdrawing said trip from operative position.

5 gage in any one of said notches, a sliding trip normally spring-pressed into position to engage the tail of the pawl as the latter moves past it so as to withdraw the pawl
 10 from engagement with the disk, a trip-withdrawing link having its rear end pivoted to one of the legs of said yoke and having a portion engaging said trip, whereby, when the yoke is moved to chamber-closing position, the trip is automatically withdrawn
 15 from the path of the pawl, and an arm fixed on said shaft and adapted to engage said link to lift the same from engagement with said trip after a predetermined movement of the lever.

34. A press of the kind described comprising a mold chamber adapted to receive the material to be pressed, an actuating lever, a closure yoke straddling said chamber and having its legs pivotally connected to said lever, a closure carried by said yoke and forming the top wall of said chamber, a plunger forming the bottom wall of said chamber and actuated by said lever, a driven shaft, and means for actuating said lever from said shaft, said means imparting a slow movement to said plunger during part of the stroke and a faster movement during other parts of the stroke.

35. A press of the kind described comprising a mold chamber adapted to receive the material to be pressed, a plunger arranged to exert pressure on the material in said chamber, a driven shaft, and actuating connections between said shaft and said plunger including a pair of elliptic gears.

36. A press of the kind described comprising a mold chamber adapted to receive the material to be pressed, a movable closure
 40 forming one wall of said chamber, a plunger

forming another wall of said chamber, a driven shaft, and means actuated by said shaft for moving said closure and plunger toward each other, said means including a pair of elliptic gears.

45

37. A press of the kind described comprising a mold chamber adapted to receive the material to be pressed, an actuating lever, a closure yoke straddling said chamber and having its legs pivotally connected to said lever, a closure carried by said yoke and forming the top wall of said chamber, a plunger forming the bottom wall of said chamber and actuated by said lever, a driven shaft, and actuating connections between
 50 said shaft and lever including a pair of elliptic gears.

55

38. A press of the kind described, comprising a mold chamber, a plunger forming the bottom wall of said chamber, a lever engaging and actuating said plunger, a closure yoke straddling the chamber and having its legs pivotally connected to said lever, a closure carried by said yoke and forming the top wall of said chamber, a driven shaft, a disk fixed on said shaft and provided with a plurality of peripheral notches, an arm journaled on said shaft and having one end connected to said lever, a pawl pivoted on the opposite end of said arm and adapted to engage in any one of the notches of said disk, a trip movable into position to engage the tail of the pawl and withdraw the latter from engagement with said disk, and means, actuated by movement of said yoke to chamber-closing position, for withdrawing said trip from operative position.
